CLAIM

The ornamental design for a display screen or portion thereof with graphical user interface, as shown and described.

DESCRIPTION

A portion of the disclosure of this patent document contains material to which a claim for copyright and trademark is made. The copyright and trademark owner has no objection to the facsimile reproduction by anyone of the patent document or the patent disclosure, as it appears in the U.S. Patent and Trademark Office patent file or records, but reserves all other copyright and trademark rights whatsoever.

The FIGURE is a front view of a display screen or portion thereof with graphical user interface showing our new design.

The broken lines showing text, portions of the graphical user interface, and the display screen or portion thereof form no part of the claimed design. The diagonal line pattern areas within the aligned rectangles show areas of contrasting appearance.
